(57) **CLAIM**

The ornamental design for an electrode-holding cap for medical diagnosis and/or treatment, as shown and described.

DESCRIPTION

FIG. 1 is a perspective view of an electrode-holding cap for medical diagnosis and/or treatment according to the present design;

FIG. 2 is a front view of the electrode-holding cap for medical diagnosis and/or treatment of FIG. 1;

FIG. 3 is back view of the electrode-holding cap for medical diagnosis and/or treatment of FIG. 1;

FIG. 4 is a left side view of the electrode-holding cap for medical diagnosis and/or treatment of FIG. 1;

FIG. 5 is right side view of the electrode-holding cap for medical diagnosis and/or treatment of FIG. 1;

FIG. 6 is top view of the electrode-holding cap for medical diagnosis and/or treatment of FIG. 1;

FIG. 7 is bottom view of the electrode-holding cap for medical diagnosis and/or treatment of FIG. 1; and,

FIG. 8 is a perspective, exploded view of the electrode-holding cap for medical diagnosis and/or treatment of FIG. 1.

The broken lines illustrate the environment and form no part of the claimed design.

1 Claim, 8 Drawing Sheets
